SHELF CLAMP FOR SUPPORTING A SIGN FRAME OR THE LIKE

Robert J. Slavsky and John R. Slavsky, Detroit, Mich., as signors to Shaw and Slavsky, Inc., Detroit, Mich., a corporation of Michigan

Application January 11, 1954, Serial No. 28,452

Term of patent 14 years

(Cl. D33—3)

Fig. 1

Figure 1 is a perspective view of a shelf clamp showing our new design, the broken line showing a sign frame being for illustrative purposes only.

We claim:

The ornamental design for a shelf clamp for supporting a sign frame on the like, as shown and described.
